F. A. NEVEU

WINDOW SHADE

Filed Feb. 11, 1926

*Inventor
Frank A. Neveu.*

By *O. Berry*

R. S. G. Attorney.

UNITED STATES PATENT OFFICE.

FRANK A. NEVEU, OF LOS ANGELES, CALIFORNIA.

WINDOW SHADE.

Application filed February 11, 1926. Serial No. 87,536.

This invention relates to a window shade of the roll curtain type and has as its primary object the provision of a roll curtain which may be employed to close or partially close an open window and which is especially applicable for use on vehicles, such as automobiles, street cars and the like.

Another object is to provide a construction whereby a rolled curtain may be securely held in variously extended positions over a window opening in such manner as to obviate flapping of the curtain by air currents.

Another object is to provide a means whereby a roll curtain may be maintained in various extended positions under tension at all times and whereby the side margins of the curtain will be retained in close proximity to a window casing and the space between the side margins of the curtain and the casing closed so as to exclude light and prevent draft along the side edges of the curtain.

A further object is to provide a mounting for roll curtains embodying means for holding a spring tensioned curtain in various extended positions which is adapted to be formed of sheet metal, which may be economically manufactured and which may be readily applied to window casings.

The invention includes, as a new article of manufacture, a combined guide and controlling element for curtains consisting of a metallic strip having a portion of its width bent to form a channel substantially U-shaped in cross-section and having a series of inwardly projecting tongues struck out from one of its side walls adapted for flatwise engagement with the end portions of the traction rod of a curtain.

With the foregoing objects in view, together with such other objects and advantages as may subsequently appear, the invention resides generally in the provision of a pair of vertical channel members adapted to be mounted on the side margins of a window opening in such manner that the side edges of a curtain may be fed into the upper ends of the channels, and in providing means in said channels engageable with the lower end of the curtain to retain the latter in various extended positions in opposition to the pull of a curtain winding spring.

The invention further resides in the parts and in the construction, combination and

arrangement of parts hereinafter described and claimed and illustrated by way of example in the accompanying drawings, in which:

Fig. 1 is a view in front elevation showing a window as equipped with the invention;

Fig. 2 is a detail in cross section as seen on the line 2—2 of Fig. 1;

Fig. 3 is a detail in vertical section as seen on the line 3—3 of Fig. 2;

Fig. 4 is a view in transverse vertical section as seen on the line 4—4 of Fig. 2;

Fig. 5 is a horizontal section as seen on the line 5—5 of Fig. 1;

Fig. 6 is a vertical section as seen on the line 6—6 of Fig. 1;

Fig. 7 is a perspective view of a fragmentary portion of the roll curtain and one of the channel members; portions being broken away.

Referring to the drawings more specifically, 8 indicates generally a window casing which may be of any suitable construction embodying the usual side frames 9 and 10, head frame 11 and sill 12 surrounding the window opening 13, and which may be fitted with any suitable window closure not necessary to be here shown.

In carrying out my present invention, I provide a pair of channel members 14 and 15 which are mounted on the side frames 9 and 10 to extend vertically along the inner margins thereof. Each of the channel members is formed of a strip of sheet metal bent

transversely, as particularly shown in Fig. 2 to form spaced parallel front and back walls 16 and 17 connected by a side wall 18, the walls 16, 17 and 18 thus forming the strip with a substantially U-shaped cross section, and providing a longitudinal channel 19.

A rearwardly projecting flange 20 may be formed on the outer margin of the back wall 17 to form with the wall 17 an angle adapted to extend around and to receive the corner forming the inner margin of the side frame 9 or 10; the channel member being designed to be positioned with the back wall 17 seating on the front face of the frame with the channel 19 opening toward the window opening and with the flange 20 seating on the inner side face of the frame.

A molding 21 may extend over the flange 20, which molding is secured in place by screws 22 or other suitable fastening which pass through the molding and through the flange 20 into engagement with the window side

frame, thereby holding the channel member in place.

Window shade brackets 23 and 24 of usual design are affixed to the upper ends of the channel members and project outwardly beyond the outer face of the front walls 16 of the latter in which brackets are supported a curtain roller 25 carrying a flexible sheet curtain 26 wound thereon; the roller 25 being fitted at one end with a trunnion 27 revolvably mounted in the bracket 24 and being provided at its other end with a cap 28 through which extends a rod 29 arranged in a longitudinal bore formed in the curtain rod. The outer end of the rod 28 is squared as indicated at 31 and seats in the bracket 23 in such manner as to retain the rod 29 against rotation. A winding spring 32 is wound around the rod 30 within the recess 29 and has one end affixed to the rod and its opposite end affixed on the cap 28, which spring is adapted to be placed under tension to yieldably oppose rotation of the curtain rod in one direction and to operate in effecting rotation of the curtain rod in the opposite direction; the spring serving as a means for winding the curtain on the roller and also for imparting a pull or tension on the curtain to maintain the latter taut when in its extended position with the lower end of the curtain held in opposition to the spring.

An important feature of the invention resides in a means for holding the curtain in various extended positions, which means is here shown as comprising a series of downwardly extending tongues 33 struck from the back wall 17 of the channel members and projecting into the channels 19 to engage the end portions of a rod 34 carried by the lower edge of the curtain; there being openings 35 in the lower corners of the curtain immediately above the rod 34 through which the tongues 33 project when engaged with the rod. Sufficient clearance is provided between the outer ends of the tongues 33 and the inner face of the front wall 16 of the channel to permit the end portions of the rod 34 to pass the tongues on raising or lowering the curtain.

In the application of the invention the curtain is formed of such width according to the space between the opposed channel members that the marginal portions of the lead of the curtain will extend into the channels 19 so as to be covered by the front wall 16 which wall will overlap the side margins of the curtain such distance that the edges of the curtain will be effectively held against being shifted out of the channels. The curtain roller is free to revolve in either direction but due to the urge of the spring 32 is normally disposed with the curtain wound thereon.

In the operation of the invention, when it is desired to lower the curtain the lead portion thereof is drawn downwardly by pulling on the rod 34 so as to effect unwinding of the curtain on the roller in opposition to the spring 32. The curtain may be thus drawn downwardly to any desired extent during which operation the end portions of the rod 33 pass readily over the tongues 33 by reason of the downward inclination of the latter. When the curtain is thus extended to its desired position the rod 33 disposed with its end portions bearing against the back wall 17, whereupon the spring 32 is allowed to effect rotation of the roller to wind the curtain thereon such distance as to bring the end portions of the rod 34 into engagement with the underside of the tongues 33 so as to hold the curtain in its lowered or extended position. The spring 32 will then act to maintain the curtain taut.

When it is desired to raise the curtain the lower end portion thereof is drawn downwardly sufficiently to effect disengagement of the bar 34 from the tongues 33, whereupon the bar is drawn outwardly to dispose the end portions thereof against the inner face of the front walls 16 of the channel members. The spring 32 is then allowed to wind the curtain on the roller the desired distance; the end portions of the rod 34 then passing upwardly through the spaces between the tongues 33 and the wall 16 until the desired point is reached whereupon the bar is engaged with a pair of opposed tongues. A hooked engagement is thus effected between the channel members and the outer end portion of the curtain.

By forming the channel members as herein set forth, they may be readily applied to the side frame members of ordinary window openings, which renders them particularly suitable for use in applying the invention to the windows of motor vehicles of the inclosed type.

While I have shown and described a specific embodiment of the invention, I do not limit myself to the exact details of construction nor the arrangement shown but may employ such changes and modifications as occasion may require coming within the scope of the appended claim. For example, while I have shown the curtain roller as disposed at the top of a window, it is clearly apparent that by inverting the channel members the curtain roller may be disposed at the bottom of the window in which event the curtain will be moved in the direction opposite that described in effecting operation thereof.

I claim:

As a new article of manufacture, a combined guide and controlling element for

curtains consisting of a strip of sheet metal having a portion of its width bent into a substantially U-shaped channel in cross-section and having a series of aligned inwardly extending tongues struck up from one of the side walls of said channel, said tongues being inclined toward the same end of said

strip, there being a clear space between the ends of said tongues and the opposite side of said strip.

10

In testimony whereof, I have affixed my signature.

FRANK A. NEVEU.
